MERCHANDISE DISPLAY SUPPORT BRACKET FOR CASH REGISTERS OR THE LIKE

George J. Perkins 44 Hawthorne Road, Barrington, Ill.

Filed Sept. 13, 1960, Ser. No. 62,241

Term of patent 14 years

(Cl. D80—9)

FIG. 1 is a perspective view of a merchandise display support bracket for cash registers or the like, showing my new design;

FIG. 2 is a front elevational view thereof;

FIG. 3 is a rear elevational view thereof;

FIG. 4 is a side elevational view thereof; and

FIG. 5 is a top plan view thereof.

The broken-line representation of containers in FIGS. 1 and 2 are for purposes of illustration only.

I claim:

The ornamental design for a merchandise display support bracket for cash registers or the like, substantially as shown and described.
